L. H. ROBINSON

ADJUSTABLE SHADE, CURTAIN, AND DRAPERY HANGER

Filed May 21, 1925

Lula H. Robinson
INVENTOR.

BY

G. P. Waldrop

ATTORNEY.

UNITED STATES PATENT OFFICE.

LULA H. ROBINSON, OF DALLAS, TEXAS.

ADJUSTABLE SHADE, CURTAIN, AND DRAPERY HANGER.

Application filed May 21, 1925. Serial No. 31,934.

To all whom it may concern:

Be it known that I, LULA H. ROBINSON, a citizen of the United States, residing at Dallas, in the county of Dallas and State of Texas, have invented certain new and useful Improvements in Adjustable Shade, Curtain, and Drapery Hangers, of which the following is a specification.

This invention relates to curtain and drapery hardware and it refers more particularly to new and novel improvements in adjustable shade and drapery hangers for residences, hospitals and other buildings wherein suitable ventilation is obtained through window openings.

The primary object of the present invention is to provide a curtain and drapery hanger having, among its combined advantages, end members whereon drapery and shade supports are movably disposed and which end members are so constructed as to be substantially braced by their connection to the ends of the supporting rods.

The invention further contemplates in addition to the above, an end supporting member which may be laterally adjusted, with respect to the rods, whereby to gauge the length of the entire assembly to suitably accord with the width of the window, and in consideration of its simplicity of construction, may be produced and sold at a very nominal cost.

With the foregoing objects and advantages in view, the invention has further novel features of construction and operation, particular reference to which is referred to herein, and illustrated in the appended drawings, wherein,

Figure 1 represents a preferred embodiment of the invention, as applied to the fac-
ing of a window.

Figure 2 is a like structure, however showing an inner central tongue, arranged to engage a rod at a point spaced from its ends, to lend additional strength to the assembly.

Figures 3 and 4 are modified forms of construction.

Figure 5 is a reversed form of support as illustrated in Figure 1.

Figure 6 is also a modified form of support, and

Figures 7 and 8 represent perspective views of the hangers illustrated in Figures 1 and 5 respectively, as the same appear in attachment to a window opening.

In previous applications, the applicant herein has disclosed various forms and modifications of curtain, shade and valance supports, all of which embody the principle of vertical adjustment with respect to their point of attachment to a window opening. The present invention also, in combination with its greater simplicity of construction and operation, employs similar methods of adjustment whereby to afford ventilation of a room by its movement downward from its normal position at the top of the window.

In proceeding with the detail description of the invention, the usual slides 1 are formed upon reverse sides of the member 3, which in turn is either formed upon the end of the rod 3^a, as in Figure 1 or slidably mounted thereon, and which members have collars upon either end thereof. These slides 1 are conformably retained behind the cleats 2, disposed upon opposite sides of the window facing, whereby to provide slidable action of the assembly thereon and which action is imparted thereto by the depending rods 17, shown only in Figures 7 and 8.

A pair of U shaped end members 4 are disposed so that the legs thereof slide within respective collars of the members 3, and are arranged to carry drapery rod supports 5, and shade supports 6 thereon, which latter are slidable horizontally to afford proper adjustment thereof to accord with drapery rods and shades of varying widths. Positive securing of the member 4 to the member 3, and the supports 5 and 6 upon the latter, is insured by the slots 7 in the said member 4 in which the retaining screws of each of the elements are adapted to slide.

A modification of the form shown in Figure 1 is depicted in Figure 2, the departure being a central tongue portion 4^a, extending from the member 4, having a collar or flat piece 8 engaged with a slot in the rod 3^a, which, in this instance, is not expansible.

Figures 3 and 5 are further modifications. Figure 3 embodying a rod 12 having a slotted end portion 9 upon which the drapery support 10 and shade support 11 are rigidly mounted. This applies also in Figure 4, but which structure employs a tongue portion similar to that indicated in Figure 2, which engages the rod.

Figure 5 illustrates the form of support employed upon a casement window, as shown in Figure 8, where the member 12 is not per-

mitted to extend beyond the facing of the window, due to the deep recessed form of the latter. The member 12 is reverse to that shown in Figure 1, which affords, not only a 5 stronger and more durable supporting element for shades and other hangings, but also permits of greater contraction to allow for narrow openings.

A further modification is shown in Figure 6, illustrating a still simpler construction.

In installing the invention, the cleats 2 are suitably secured upon either side of the opening, and the rod 3^a is expanded, as in Figure 1, so that the slides 1 snugly abut against the cleats, and the flange thereon conforms behind the latter. The rod 3^a is then secured from contraction by the screws 5^a. In this position the end members 4 are 20 flush with the window facing, and as obvious in Figure 7, no portion of the assembly protrudes a great distance from the window, thus insuring a greater weight carrying hanger. The rods 16 are mounted upon their 25 respective supports, and the shade is mounted upon the supports 6, at which time the assembly is moved to the top of the window by the rods 17, depending from the slides 1.

It is obvious, in view of the foregoing, that the preferred structure shown in Figure 1, is both durable and simple in construction and does not present an unsightly appearance upon a window, and also affords a simple and practical means for mounting shades, 30 curtains, draperies and valances.

What I claim is:

1. A hanger for shades and the like including a horizontal rod having vertical parts at its ends, horizontally disposed collars on the ends of the vertical parts, U-shaped members having their legs disposed horizontally and extending through the respective collars, cleats formed for vertical 40 secured to the sides of a window frame, slides on the vertical parts engaged with the cleats, and brackets on the legs of the U-members.

2. In a hanger for shades and the like, vertical members having spaced upper and lower horizontal collars, cleats formed for vertical secured to the sides of a window frame, slides on the members engaged with the cleats, U-shaped members having their legs disposed horizontally and extending 50 through the respective collars, and brackets on the legs of the U-members.

3. A hanger for shades and the like including end devices composed of vertical parts, horizontally disposed upper and lower collars on the vertical parts, U-shaped members having their legs disposed horizontally and extending through the respective collars, cleats formed for vertical secured to the 60 sides of a window frame, slides on the vertical parts engaged with the cleats, a horizontal support for the end devices, means to connect the end devices to the support, and brackets on the U-members.

In testimony whereof I affix my signature.

LULA H. ROBINSON.
